EXPANSION JOINT AND FILLER BRIDGE

Robert R. Robertson, Chicago, Ill., assignor to
The Translode Joint Company, Chicago, Ill., a
corporation of Illinois

Application July 7, 1934, Serial No. 734,096

13 Claims. (Cl. 94—18)

The present invention relates to an improved road expansion joint including end closure means for the joint void, and a filler supporting bridge comprising bridge members which are releasably supported on the core forming plates and are left in position with the removal of the core plates allowing notched portions of the bridge members to be deflected inwardly to be interlocked with one another to form an arched support for the reception of a filling of plastic material to close the upper portion of the joint void which is left in the concrete above the load transmission base unit in which the core plates are originally supported.

It is an object of this invention to provide a road expansion joint forming unit including bridge members which are removably supported on the core plates and are left in position with the removal of the core plates after the pouring of concrete to permit portions of the bridge members to be bent inwardly to bridge the void and to lockingly interfit one another to form a suitable support for a filling of a plastic material to partially fill the upper portion of the void between adjacent concrete sections of a road.

It is also an object of this invention to provide a road expansion joint with bridge members adapted to be partially embedded in the concrete and having portions thereof projecting into the expansion joint void to be interlocked with one another to bridge the joint void and afford an arched support for a filling of plastic material to complete the upper portion of the expansion joint between concrete road sections.

It is a further object of this invention to provide an expansion joint void spanning unit including angle members having notched flanges adapted to be moved into interfitting relation with one another with portions of the notched flanges bent over to interlock the bridge members with one another to form a support for a plastic filling for closing the upper portion of the road expansion joint.

It is an important object of this invention to provide a road expansion joint forming mechanism including a load transmission base for removably supporting a void forming core unit in place between concrete road sections, said core unit having removably supported thereon filler supporting bridge members which are adapted to have portions thereof permanently embedded in the concrete sections, and furthermore having notched portions projecting into the void, whereby the notched portions of the bridge members are bent into interfitting relation with re-

spect to one another to form a support for a filling of plastic material to close the upper portion of the expansion joint.

Another important object of the invention is the provision of an improved type of road joint 5 filler supporting bridge unit including angle members comprising base flanges having pockets formed therein and adapted to be embedded in concrete and bridge flanges adapted to project into an expansion joint void, with each of said 10 bridge flanges having the upper margin notched to form spaced flaps or tongues which are adapted to permit adjacent bridge flanges to interfit with one another allowing the flaps to be deflected to form an interlocked filler ridge to 15 permit a filling of plastic material to be deposited in the upper portion of a road joint to close the same.

Other and further important objects of this invention will be apparent from the disclosures 20 in the specification and the accompanying drawings.

The invention (in a preferred form) is illustrated in the drawings and hereinafter more fully described.

On the drawings:

Figure 1 is a vertical detail section of a concrete road structure just after the pouring of concrete and illustrating a load transmission base unit having a removable core unit supported 30 therein on which improved bridging members are releasably supported, during the pouring of concrete, by a removable core cap.

Figure 2 is a similar section of the completed expansion joint with the core unit and core 35 closure cap removed and with the bridge members projecting across the expansion joint void and interlocked with one another to form a support for a filler of plastic material for closing the upper portion of the expansion joint.

Figure 3 is a fragmentary plan view of a portion of one of the bridge members before being bent into shape.

Figure 4 is a top plan view of the bridge unit showing the interlocking relation of the notched 45 flanges of the bridge members.

Figure 5 is a detail section of the filler bridge unit showing the notched flanges interfitting one another prior to the deflecting of the flaps.

Figure 6 is an enlarged fragmentary transverse 50 section of the interlocked bridge portion of the bridge unit illustrated in Figure 4.

Figure 7 is a fragmentary top plan view of a load transmission expansion joint, before the pouring of concrete, illustrating the temporary 55

position of the bridge members and also showing the adjustable end closure unit for closing the outer end of the expansion joint core unit.

Figure 8 is an end elevation of the closed end of the expansion joint mechanism illustrated in Figure 7.

Figure 9 is a fragmentary side elevation of the joint mechanism illustrated in Figure 8.

Figure 10 is a fragmentary perspective view of a modified form of an expansion joint filler supporting bridge unit.

As shown on the drawings:

In Figures 1 and 2, the concrete road sections 1 are illustrated disposed on opposite sides of an expansion joint constructed by the use of improved expansion joint forming mechanisms embodying the principles of this invention.

The present invention covers an improved type of an air expansion joint for roads and similar concrete constructions and includes in combination an improved load transmission base unit in which a removable core unit is supported for temporarily supporting in position, during the pouring of concrete, improved bridge members adapted to be moved into interlocking engagement with one another to span the void resulting from the removal of the core unit from between the concrete road sections, to permit a filling of a bituminous or plastic material to be deposited on the bridge unit to close the upper portion of the expansion joint.

The base unit of the road joint former serves as a load transmission mechanism between the adjacent sections of the concrete road construction and in the present joint comprises an elongated base member consisting of a solid base plate 2 constructed of sheet metal or other suitable material.

The longitudinal margins of the base plate 2 are bent upwardly and then inwardly toward one another to form oppositely positioned guide channels 3 which provide oppositely positioned guide spaces or grooves 4. The longitudinal margins of the top plates of the base guide channels are cut away at spaced intervals, with the notches in one margin being staggered with respect to the notches in the opposite margin to provide staggered flaps or extensions which are bent upwardly at substantially right angles to form staggered retaining tongues or lugs 5, the upper margins of which are curled inwardly to form curved lips 6. The outwardly projecting retaining tongues 5 on each side of the middle portion of the base unit are separated by notches or recesses for the reception of anchor units which will hereinafter be more fully described. The grooved or channel base member forming part of the base unit is usually provided in a standard length of substantially half the width of the road and extends from the outer side of the road inwardly to the road center strip. The base unit, however, may be provided in shorter lengths if so desired.

The base member has associated therewith a plurality of load transmitting mechanisms consisting of a plurality of anchor shoes or holders which are movable or shiftably engaged in the base section and are arranged longitudinally in offset or staggered relation with respect to one another. The anchor shoes or holders are of substantially identical construction and are arranged with the adjacent shoes reversed with respect to one another as clearly illustrated in Figure 7. Each of the anchor shoes is constructed of metal and comprises an angle bar including

a base flange 7 and an upright flange or web 8 integral with the base flange. The upper margin of each of the upright flanges or webs 8 is provided with angular cuts and the material above the cuts is bent outwardly to provide a plurality of anchoring blades or wings 9. The anchoring blades 9 project outwardly from one side of the web 8 leaving the opposite side of the web flat as clearly illustrated in Figures 1 and 2.

The anchoring shoes are transversely shiftably or slidably mounted within the grooved base section with adjacent shoes reversed with respect to one another, so that the anchoring blades or wings 9 project outwardly leaving the flat sides of the upright webs or flanges of the anchoring shoes facing inwardly. As clearly illustrated in Figure 1, the anchoring shoes are staggered with respect to one another so that the upright flanges 8 may be seated in the notches provided in the top flanges of the base section between the retaining tongues or flaps 5 and slightly to the outside of said tongues 5 to afford retaining spaces between the inner surfaces of the upright flanges 8 and the outer faces of the retaining tongues 5 of the base section.

The outermost anchoring shoe, in each of the base sections of the device, has connected therewith a closure means for closing the outer end of the void forming core unit, and the outer end of the void resulting from the removal of the core unit after the pouring of concrete which forms the upper or crown section of the road. The closure means for the core unit comprises a primary closure plate 10 (Figures 7 to 9 inclusive) which is welded or otherwise rigidly secured to the end 11 and 12 to form an upper flap 13 and a lower flap 14 as clearly illustrated in Figure 8. The portion of the plate between the cuts 11 and 12 is bent at substantially right angles to form a wing plate 15 having an anchoring blade 16 integrally formed thereon and projecting outwardly to serve as a means for anchoring the wing plate 15 in the concrete of a road section. The opposite vertical margin of the main closure plate 10 has slideable interfitting or telescoping engagement with a hollow or U-shaped plate receiving pocket or socket 17. The wall of the guide pocket 17 nearest the concrete section of the road is provided with an extension plate 18 (Figure 7) which lies flat against the inner side of the main plate 10 and has integrally formed thereon a wing plate 19 positioned substantially parallel to the wing plate 15. Integrally formed on the wing plate 19 is an outwardly directed anchoring blade 20 or wing 20 which is adapted to be embedded in the concrete forming an adjacent concrete section of the road for the purpose of holding the guide pocket 17 in position.

The void forming core unit of the joint forming mechanism comprises a pair of metal plates 21 which are spaced apart and have the lower margins thereof projecting downwardly between the flat surfaces of the upright anchor shoe flanges 8 and the staggered spring-like retaining tongues or lugs 5 as clearly illustrated in Figure 1 to hold the lower margins of the core plates properly spaced apart. The outer vertical edges of the core plates 21 are in contact with the inner face of the main or primary closure plate 10. The outer sides of the upper margins of the two core plates 21 are cut out to provide seats or shoulders 22. The seats or shoulders 22 provided near the upper margins of the core plates 21 afford temporary seats for a pair of

oppositely positioned bridge members and cap supports each comprising a base flange 23 having cups or sockets 24 struck downwardly therefrom to form recesses for the reception of concrete to hold the base flange 23 securely embedded in a concrete road section 1. Integrally formed with the base flange 23 is a bridge flange 25, the upper margin of which is provided with a plurality of spaced notches 26 leaving a plurality of spaced flaps or tongues 27.

For the purpose of holding the bridge members temporarily in position on opposite sides of the upper portion of the core unit, a removable channel shaped form or closure cap 28 is engaged over the spring-like upright bridge flanges 25 with the side flanges of the removable cap projecting downwardly to seat upon the horizontal base flanges 23 of the bridge forming member. As clearly illustrated in Figure 1 the side flanges of the cap 28 hold the bridge forming flanges 25 clamped against the outer surfaces of the upper portion of the core plates 21. Welded or otherwise secured within the closure cap 28 at spaced intervals are a plurality of spring-like spacing boxes or tubes 29. The spring-like spacing boxes or members 29 project downwardly between the upper margins of the core plates 21 to hold the upper margins properly spaced apart.

With a load transmission base unit supported on the road subgrade, and with the core plates 21 removably seated thereon to support the bridge forming angle members in position on opposite sides of the upper portion of the core plates by means of the removable closure cap 28, concrete is poured to form the upper section of the road on opposite sides of the road expansion joint forming mechanism. After the pouring of the concrete as illustrated in Figure 1, the concrete is allowed to set a desired amount. The closure cap 28 together with the spacing boxes or member 29 forming a part thereof are first removed from engagement with the upper margins of the core plates 21 thereby permitting access to be had to the core plates. The core plates are next moved inwardly toward one another and are lifted upwardly out of the core space formed between the concrete road sections 1 leaving the air expansion chamber or void 30 above the base unit. With the removal of the core closure cap and the core forming plates, the bridge flanges 23 remain embedded in the concrete and the flanges 25 are left projecting into the upper portion of the void 30. The end closure plates 10 and 18 at the end of the core unit are also left in position to close the outer end of the expansion void 30.

For the purpose of closing the upper portion of the expansion void 30, the bridge flanges 25 of the bridge members are bent inwardly toward one another to span the void 30, and the upper notched margins of the flanges 25 intersect one another as illustrated in Figure 5 after which the tongues or flaps 27 of one flange are bent downwardly over an adjacent flange as illustrated in Figure 6 to interlock the bridge flanges 25 and form an arched bridge closure for the upper portion of the expansion void 30. The space above the bridge is now partially filled by means of a filling of plastic material such as asphalt or the like to form a compressible and expandable filler block 31.

Figure 10 illustrates a modified form of an expansion void bridge unit consisting of a pair

of angle members comprising base flanges 32 and bridge flanges 33. Integrally formed on the upper margin of one of the bridge flanges 33 is a bridge strip 34 which has retaining lugs 35 struck outwardly therefrom to be projected through slots or apertures 36 provided at spaced intervals in a bridge strip 37 integrally formed on the upper margin of the second bridge flange 33.

The base flanges 32 of the bridge angle members are adapted to be embedded in concrete of opposite or adjacent sections of a road section while the bridge members 33 are left to project into the void between the sections. When the bridge fenders 33 are deflected inwardly, the bridge strips 34 and 37 are moved into abutting engagement with respect to one another so that the lugs 35 project through the slots 36 and are bent over to hold the bridge strips clamped together to form a closed arched bridge unit for the support of a plastic filler to close the upper portion of a road expansion joint.

This improved invention embodies an air expansion joint forming mechanism for roads including a load transmission base unit having a removable core unit supported thereon with the outer end of the core unit closed by means of an adjustable closure means supported on the base unit, and retainable in position after the removal of the core unit for the purpose of closing the outer end of the expansion void. The joint forming mechanism furthermore includes improved bridge units constructed of bridge members which are partly embedded in the concrete sections of the road, and have bridge forming portions which project into the expansion void and are interlocked with one another to provide an arched support for a plastic filler used to close the upper portion of the expansion joint.

It will, of course, be understood that many details of construction may be varied through a wide range without departing from the principles of this invention, and it is therefore not the purpose to limit the patent granted hereon otherwise than necessitated by the scope of the appended claims.

I claim as my invention:

1. A concrete construction joint former for embedding in concrete and including in combination a base section, an anchoring unit shiftably mounted therein, a core unit having open ends and removably supported on said anchoring unit and removable from the concrete to leave an expansion void above the base section, means carried by the anchoring unit for closing one end of the core unit and the expansion void resulting from the removal of the core unit, and bridge members releasably carried by the core unit and retainable in position partially embedded in concrete when the core unit is removed after the pouring of concrete, said bridge members adapted to be deflected into interlocking engagement with one another to form an arched bridge for supporting a filler of plastic material to close the upper portion of the expansion joint void resulting from the removal of the core unit.

2. A concrete construction joint former for embedding in concrete and including in combination a base section, an anchoring unit shiftably mounted therein, a core unit having open ends and removably supported on said anchoring unit, means carried by the anchoring unit for closing one end of the core unit, and bridge members releasably carried by the core unit and

retainable in position partially embedded in concrete when the core unit is removed from a concrete construction to leave an expansion space therein, said bridge members adapted to have free portions thereof deflected inwardly to bridge the expansion space, said bridge members including interfitting means for interlocking the bridge members with one another to form a bridge to serve as a support for a plastic filler for closing the upper portion of the expansion space.

3. A concrete construction joint forming mechanism for embedding in concrete and comprising a load transmission base, a core unit 15 removably supported thereby and removable from the concrete construction to provide an expansion void therein, and filler supporting members temporarily carried by the core unit and remaining partially embedded in the concrete to be supported thereby when the core unit is removed, said filler supporting members including deflectable portions projectible into the void toward one another to span the same, said portions of the filler supporting members formed 25 to interlock one another to permit a plastic filler to be engaged on said portions in the upper portion of the expansion joint to close the same.

4. A concrete construction joint forming mechanism for embedding in concrete and comprising a load transmission base, a core unit 30 removably supported thereby and removable from the concrete construction to leave a void therein, filler supporting members temporarily carried by the core unit and retainable in position 35 partially embedded in the concrete and supported thereby when the core unit is removed, and means forming a part of the filler supporting members and projecting into the void into engagement with one another for interlocking the members with one another to span the expansion void and form a support for a plastic filler for closing the upper portion of the expansion joint.

5. A road joint former comprising in combination a core unit for removable engagement in concrete, filler supporting members including deflectable parts temporarily engaged with the core unit, said members adapted to remain in position in the concrete and be supported thereby when the core unit is removed therefrom, and means on said deflectable parts for interlocking the same one to another when the deflectable parts are bent inwardly to span the void resulting from the removal of the core unit from the concrete.

6. A concrete construction joint former comprising a load transmission base unit, a core unit thereon for embedding in concrete and removable to leave a void in the concrete, filler supporting members releasably carried by the core unit and partially embedded in the concrete and supported thereby when the core unit is removed leaving portions of said members projecting into the void to be deflected into contact with each other, and tongues integrally formed on the filler supporting members for interlocking the filler supporting members one with the other to form a filler supporting bridge spanning the joint void resulting from the removal of the core unit.

7. A concrete construction joint former comprising a load transmission base unit, a core unit removably supported thereon to be embedded in concrete and removable from the concrete to

leave a void therein, and filler supporting members releasably carried by the core unit and partially embedded in the concrete to be supported thereby when the core unit is removed, said filler supporting members deflectable toward one another into the void and having staggered tongue-like means for interlocking the filler supporting members one with another to form a filler supporting bridge to close the upper portion of the joint void resulting from removal of the core unit.

8. A concrete road joint former comprising in combination a core unit for embedding in concrete and removable from the concrete to leave a void therein, and filler supporting members 15 carried by the core unit and projecting into and retainable by the concrete and having portions projecting into the void, said portions deflectable toward one another into the void and having spaced tongues integrally formed thereon 20 with the tongues of one filler supporting member staggered with respect to those of an adjacent member to permit the filler supporting members to be interlocked with one another with the tongues of one member bent downwardly over an 25 adjacent member.

9. A road joint filler bridge unit comprising in combination a pair of angle members partly embedded in opposite sections of concrete, said angle members including base flanges having 30 staggered sockets therein and bridge flanges including notched marginal portions adjustable into interfitting relation with one another when the bridge flanges are deflected toward one another to span the space between adjacent concrete sections to form a support for a filler for closing the upper portion of a road joint.

10. A road joint filler bridge unit comprising in combination a pair of angle members including supporting flanges to be embedded in opposite sections of concrete, said angle members also including bridge flanges having spaced deflectable tongue means for lockingly interfitting the bridge flanges together to form a support for a plastic filler for closing the upper portion of the 45 space between opposite sections of concrete.

11. In a road expansion joint mechanism of the class described including in combination a filler supporting bridge unit comprising angle members including base flanges and deflectable 50 bridge flanges, said bridge flanges having the longitudinal margins thereof formed to lockingly interfit one another when the bridge flanges are bent toward one another to form an arched filler support.

12. A road joint filler bridge unit for use in a concrete road and comprising in combination a pair of angle members comprising base flanges having spaced sockets formed therein, and bridge flanges having spaced tongues formed on the 60 longitudinal margins thereof with the tongues of one bridge flange staggered with respect to the tongues of the opposite bridge flange to permit the bridge flanges to interfit one another and be interlocked when the tongues of one bridge 65 flange are bent downwardly to overlap an adjacent bridge flange.

13. A road joint filler supporting bridge unit for use in a concrete road and including angle members each consisting of a base flange, having 70 socket means formed therein and a bridge flange having tongue members for interlocking the angle members one to the other.

ROBERT R. ROBERTSON.
